[57] CLAIM

The ornamental design for jeans, substantially as shown and described.

DESCRIPTION

FIG. 1 is a front perspective view of jeans showing our new design;

FIG. 2 is a rear perspective view; and

FIG. 3 is a side perspective view, the opposite side being a mirror image thereof.

Inside the jeans at the top stitching is omitted for convenience of illustration.

The characteristic feature of our design is the configuration and contrasting tone of the front and seat panels.
